UNITED STATES PATENT OFFICE.

EMORY L. TOWNSEND, OF LOS ANGELES, CALIFORNIA.

ARTIFICIAL TOOTH.

No. 805,171.

Specification of Letters Patent.

Patented Nov. 21, 1905.

Application filed December 30, 1903. Serial No. 187,231.

To all whom it may concern:

Be it known that I, EMORY L. TOWNSEND, a citizen of the United States, residing at Los Angeles, in the county of Los Angeles, State 5 of California, have invented new and useful Improvements in Artificial Teeth, of which the following is a specification.

The object of my invention is to provide a backing and facing for artificial teeth so constructed that if the facing of porcelain is fractured or damaged it may be expeditiously and conveniently removed from the backing and another facing conveniently substituted. I accomplish this object by the devices described herein, and illustrated in the accompanying drawings, in which—

Figure 1 is a vertical longitudinal section of one of my improved teeth, showing it applied to a tooth in the fragment of the jaw. Fig. 2 is a longitudinal vertical section of a slightly-modified form of tooth detached from the jaw. Figs. 3, 4, 5, and 6 are longitudinal vertical sections of my improved tooth ready for use.

In the drawings, A is the jaw, and B is the root of a tooth in place therein, to which is affixed my improved artificial tooth in the usual manner. This tooth is composed of the porcelain front C, from the back of which projects a single pin of wire D, having a head D', which head is just small enough to pass into the opening in the socket E, secured to the metal back F. This socket is preferably constructed in shape the frustum of a cone, with a central opening therethrough in shape the frustum of a cone with the smaller part of the opening presented to the porcelain facing, and it is secured to the metal back by soldering. After the socket is secured to the metal back the aperture in the socket is filled with plastic cement G, and the facing presented to the porcelain is also coated with plastic cement and the porcelain facing is then pressed upon the same and the head of the pin is forced into the socket, thereby forcing a portion of the cement out of the socket and making a complete bond between the porcelain facing and the metal back as soon as the cement has hardened. I have found in practice that a single pin will unite the porcelain facing to the metal back so securely that the facing will break before the pin can be withdrawn from the socket and that after the porcelain is removed from the pin the body of the pin will break without pulling the head out of the socket. If at any time the porcelain front should break, by removing the

fragments from the backing the pin can be drilled out of the socket and the cement removed therefrom, when a new porcelain facing can be secured thereto, as before described. 60

In Figs. 1, 4, and 6 I have shown the lower back of the porcelain facing as a plain surface. In Figs. 2, 3, and 5 I have shown the facing as provided with a slight circular recess C'', with a corresponding projection F' 65 in the metal back to pass thereinto, the object of which is to provide an additional safeguard against the facing turning upon the back.

In Figs. 1, 2, 5, and 6 I have shown a socket as being wholly inclosed within the metal back so as to leave the upper front part of the metal back a plain surface, which is the preferable form of making the tooth where space sufficient therefor is had; but where the space is contracted, as in front teeth, I prefer to 70 make a depression C' in the back of the porcelain facing and secure the socket to the metal back so that it projects forwardly therefrom and will be partly seated in the depression of the facing, as shown in Figs. 3 and 4. 80

Having described my invention, what I claim as new, and desire to secure by Letters Patent, is—

1. The combination with an imperforate recessed metallic back, a socket secured in the 85 recess, said socket having a countersunk recess at the inner end of the opening through it, of an artificial tooth having a headed stud, the head of which is of a size to just enter the 90 hole in the socket, and the space between the head of the stud and within the socket filled with a cement which upon hardening holds the stud permanently in place.

2. The combination with an imperforate metallic back, a socket secured therein, said 95 socket having a countersunk recess at the inner end of the opening through it, of an artificial tooth having a headed stud, the head of which is of a size to just enter the hole in the 100 socket, and the space between the head of the stud and within the socket filled with a cement which upon hardening holds the stud permanently in place, and means comprising a recess and projection for preventing a tendency of the tooth to turn upon its support. 105

In witness that I claim the foregoing I have hereunto subscribed my name this 21st day of December, 1903.

EMORY L. TOWNSEND.
